UNITED STATES PATENT OFFICE.

HOWARD D. COLMAN, OF ROCKFORD, ILLINOIS, ASSIGNOR, BY MESNE ASSIGNMENTS, TO HIMSELF, LUTHER L. MILLER, AND HARRY A. SEVERSON, COPARTNERS DOING BUSINESS AT ROCKFORD, ILLINOIS, AS BARBER-COLMAN COMPANY.

WINDER.

1,187,971.

Specification of Letters Patent. Patented June 20, 1916.

Application filed July 31, 1903. Serial No. 167,703.

To all whom it may concern:

Be it known that I, HOWARD D. COLMAN, a citizen of the United States, residing at Rockford, in the county of Winnebago and 5 State of Illinois, have invented certain new and useful Improvements in Winders, of which the following is a specification.

In my copending application Ser. No. 649,080, filed September 13, 1911, as a continuation of my earlier application Ser. No. 112,705, of June 21, 1902 there is disclosed a winder arranged to unwind yarn from bobbins and wind the yarn upon a warp beam, the bobbins being supported in an endless 15 movable series of boxes, and the threads extending from the bobbins being guided to the warp beam in the form of a single flat sheet. In said winder means is provided for detecting the exhaustion of a thread, and 20 for automatically tying a new thread to an exhausted thread; said means including a knot-tying mechanism, reciprocable transversely of the sheet of threads.

One of the objects of the present invention is to produce an automatic winder in which the bobbins shall be supported in the same general manner as in the ordinary spooler, namely, in bobbin-holders arranged in two rows at opposite sides of the spooler 30 or winder frame. In pursuance of this object I have provided a thread-uniting mechanism arranged to travel in an endless path or circuit so located with reference to the rows of bobbin-holders that said mechanism 35 travels into operative relationship to the bobbin-holders or threads successively. Such an organization of parts may be used irrespective of the character of the container or containers on which the yarn from the 40 bobbins is wound. In the embodiment selected to illustrate the invention, the yarn is wound upon a warp beam.

A further object of the invention is the production of means for confining thread 45 breakages to a given region, in order that reserve threads may be automatically joined to the ends of broken threads.

The invention further refers to a means for supplying thread to a continuously-operating winding mechanism when the travel of a portion of the thread being wound thereby is stopped.

In the embodiment herein shown of this

invention, the threads pass from bobbins lying loosely in suitable pockets to a section beam, upon which the threads are wound as warp threads, each warp thread being made continuous by joining a number of bobbin threads together end to end as the winding progresses.

For convenience in description, I will call the threads being wound from the bobbins to the section beam "active" threads, and an active thread which has been wholly unwound from its bobbin or which has become broken will be designated as "exhausted." Threads coming from full bobbins, their ends held in position to be attached to an exhausted thread, will be termed "reserve" threads.

In the present embodiment, each active thread passes from its bobbin to a positively-driven V-grooved roller; from this roller to a second similar but slightly smaller roller, also positively driven, downwardly from this roller and up again, forming a loop to provide a supply of thread for the continuously-operating winding mechanism when an active thread becomes exhausted and its end is held until a reserve thread is 80 tied to the end of said exhausted thread; and thence to said winding mechanism. As stated, the bobbins lie loosely in suitable pockets, two of which pockets are provided to every running (active) thread, one to contain the bobbin of the active thread and the other that of a reserve thread. Reserve threads successively become active threads, and for this reason each of the two pockets 85 contains the bobbin of an active thread and 90 that of a reserve thread alternately.

Two air tubes connected with a means for drawing the air therefrom, as, for instance, an exhaust fan, extend transversely of and lie beneath the active and the reserve 95 threads. One of said air tubes has transverse slits in its upper side, each of which slits coincides with one of said active threads. The other air tube has a series of openings, each for receiving the end of a 100 reserve thread, a portion of which thread lies parallel with but at a little distance from its adjacent active thread. The ends of the reserve threads are held in their air tube by the air current in said tube, and 105 when an active thread exhausts, its loose

end is drawn into the air tube first mentioned and is there held by the air current in said tube.

Several knot-tying mechanisms, each 5 mounted on a carriage supported upon an endless track and adapted to travel continuously in one direction on said track, pass directly beneath the active threads. Each tying mechanism carries an actuating wheel 10 adapted to be engaged by a detent pin slidably mounted in a suitable opening in the supporting framework beneath each active thread, which pin is thrown forward by the detector mechanism into the path of said 15 actuating wheel whenever an active thread exhausts.

The tension of winding upon the active threads holds said threads slightly above the passing knot-tying mechanisms; said 20 tension, acting through the detector mechanism, also holding the reserve thread at a little distance above the active threads. When an active thread becomes exhausted, the tension upon it fails, and the free end 25 of said active (exhausted) thread is drawn downward by the air current into the proper slit in the air tube for the active threads. The diminution of tension upon said exhausted thread permits the detector mechanism 30 to place the companion reserve thread by the side of said exhausted thread, the detector mechanism depressing the exhausted thread so that both threads lie in the path of the knot-tying mechanisms. While 35 the end of the exhausted thread is thus held for a moment until the next succeeding traveling knot-tying mechanism shall unite it to the adjacent reserve thread, the loop hereinbefore mentioned in said exhausted 40 thread supplies thread to the continuously-operating winding mechanism. A complete tying mechanism is supported upon each of the knotter carriages, and a machine will be provided with as many tying mechanisms 45 as are necessary to unite the ends of exhausted threads to the ends of reserve threads before the thread loop just mentioned is taken up by the winding of all the threads on the section beam. When the 50 tying-mechanism has united the threads, the tension upon the newly-made active thread is restored, said active thread raised from the path of the tying-mechanisms, and the detector mechanism moved into its normal 55 position. The operator now removes the empty bobbin from its pocket, and substitutes a full (reserve) bobbin, placing the thread from the reserve bobbin in position upon the detector mechanism.

60 In the accompanying drawings, Figure 1 is a top plan view showing the general outlines of a mechanism embodying the features of my invention. Fig. 1 is an end elevation of the warp beam and its driving drum. Fig. 2 is a similar view upon a

larger scale showing one of the "sides" of said mechanism. Fig. 3 is a vertical section of the thread mechanism, on dotted line 3 of Fig. 2, which mechanism is repeated for each running thread. Fig. 4 is a transverse view on dotted line 4-4 of Fig. 3. Fig. 5 is a detail view of the mechanism for throwing the detent pin into the path of the actuating wheel for the knotter mechanism. Fig. 5^a is a detail view of said detent pin and the shoe for restoring said pin. Fig. 6 is a detail view showing the rear V-grooved roller and a portion of the mechanism for holding the reserve thread at a distance from the active thread by means of the tension upon said active thread. Fig. 7 is a detail view showing the air tubes for the active threads in longitudinal section. Fig. 8 is a top plan view of the mechanism shown in Fig. 6, also showing the guide channel for the supply loop in the active thread. Fig. 9 is a transverse section through said guide channel showing the rider-weight for the thread. Fig. 10 is a vertical detail section on dotted line 10-10 of Fig. 2. Fig. 11 is a perspective view taken on a transverse vertical sectional line through one of the "sides" of the machine, the active and the reserve threads being indicated by full lines, the parts of the mechanism being in the positions they assume when the winding is in progress. Fig. 12 is a view similar to the last preceding figure, but showing the parts of the mechanism in the positions which they assume when the active thread exhausts. Fig. 13 is a top plan view of one of the knotter-carriages with its knot-tying mechanism. Fig. 14 is a section through said knot-tying mechanism, on dotted line 14-14 of Fig. 13. Fig. 15 is a side elevation of the knot-tying mechanism. Fig. 16 is a top plan view of said mechanism, the parts being in the positions they are shown to occupy in the last preceding figure. Fig. 17 is a side elevation of the knot-tying mechanism similar to Fig. 15, save that the elements of the thread-clamp are closed together in clamping position, and the knotter shaft has been rotated slightly. Fig. 18 is a top plan view of the knot-tying mechanism, showing the parts in the positions which they occupy near the completion of the tying operation. Fig. 19 is a side elevation of the knot-tying mechanism, showing the parts in the positions in which they are represented in the last preceding figure. Fig. 20 is a side elevation of the knot-tying mechanism taken from the side opposite to that shown in Figs. 15, 17 and 19. Fig. 21 is a vertical sectional view through the tying mechanism on the axial line of the knotter shaft. Figs. 22 and 23 are side elevations of the cam cylinder and the tying-bill, showing said tying-bill in different positions. Fig. 24 is an edge view of a spring for the 130

latch upon the thread-holding arm. Fig. 25 is a perspective view showing the tying-bill in its initial position, with the active thread and the reserve thread in place to be acted upon by the tying-mechanism. Fig. 26 is a view similar to the last preceding figure, save that the tying-bill has been rotated through about one fourth of a revolution. Fig. 27 illustrates the tying-bill after it has been rotated through one-half a revolution, also showing the thread-clamp about to grasp the threads. Fig. 28 shows the tying-bill after three-fourths of a revolution, the thread-clamp having clamped the threads and the shearing and clamping jaw being open to receive them. Fig. 29 shows the tying-bill at the completion of its first revolution. Fig. 30 shows the tying-bill after it has been rotated through about one and one-fourth to one and one-third revolutions, the shearing and clamping jaw having clamped and severed the threads, and the thread-clamp being represented in the act of stripping the threads from the point of the tying-bill. Fig. 31 illustrates diagrammatically the form of knot tied by the mechanism.

In the production of a winder embodying the features of my invention, I provide a supporting frame 1 having two "sides" 2 and 3. The length of the frame, it will be understood, is governed by the number of threads to be wound. The drawings illustrate mechanism for only a few threads; in practice the frame will be made of sufficient length to accommodate about 200 or more threads on each side. An endless track 4, having straight parallel sides connected by curved ends, is adapted to support a number of knotter carriages 5. To move the knotter carriages upon the track 4, I provide an endless chain 6 mounted upon two sprocket wheels 7, which chain and sprocket wheels are driven in any suitable manner, as by belt and pulley (not shown). The knotter carriages 5 are pivotally connected with the chain 6, and are adapted to move about the track 4 continuously in one direction. At one end of the machine is mounted a winding mechanism 8 of any suitable construction. In practice, this mechanism may be any common or suitable means for rotating a section beam. A comb 9 is located in front of the winding mechanism, and properly spaces the threads running to said mechanism.

A knot-tying mechanism, to be next described, is mounted upon each of the carriages 5. A fixed shaft 10 is supported between the upper ends of two brackets 11 and 12 extending upwardly from the upper face of the knotter carriage 5. Upon this shaft is rotatably mounted a sleeve 10⁰ upon which is fixed the actuating gear wheel 13, said gear wheel having upon its periphery skew

gear teeth 14 and having in its peripheral face a wave cam groove 15. A disk 16 is secured upon the sleeve 10⁰ beside the actuating gear wheel 13, said disk carrying four radially extending forks 16, for receiving a deton pin to a lever-limiter described as rotating said actuating wheel to operate the knotter mechanism.

An arm 17 (Fig. 14) clamped to and extending upwardly from the shaft 10 supports at its upper end a rotary knotter shaft 18, (Fig. 21) upon which shaft is fixed a pinion 19. The gear teeth 14 of the actuating gear wheel 13 and the pinion 19 are skewed and are adapted to mesh each with the other. The forward end of the knotter shaft 18 is bent substantially at a right angle with the body of the shaft to receive a tying-bill 20, which tying-bill tapers toward its end and is bifurcated to provide 21 on one side a shear-edge 22 and on the other side a clamping edge 23, having a shear edge on one side and a clamping edge on the other side to correspond with the similar shear edge and clamping edge of the tying-bill, is pivotally mounted within the bifurcation in said tying-bill upon a pin 24. A cam-barrel 25, is fixed on the arm 17, the knotter shaft passing through an opening 26 eccentric to the cam-barrel. The jaw 23 has an extension or wing that lies within the cam-barrel 25, said jaw being opened and closed in the rotation of the tying-bill by reason of the eccentricity and interior conformation of said cam-barrel. At one of its ends the arm 17 is provided with a bracket 27 (Fig. 20) fixed with relation to said arm. A pinole 28 extends longitudinally through said bracket, and a hub 29 having two bell crank 125 arms 30 and 31 is loosely mounted on said pinole. One of said arms (30) carries an anti-friction roller 32 adapted to lie within the cam-groove 15 of the retarding gear 13. The other one (31) of said arms carries the thread-clamping arm 33 (Fig. 15) having at its forward end the two upwardly extending clamping fingers 34. The thread-clamping arm is connected with the outer end of the arm 31 by means of the pivot pin 35, and the upwardly projecting end of this pin is made angular in form for a purpose to be later specified. A movement of the actuating gear 13 oscillates the hub 29 upon its pinole 28.

A thread-holding arm 36 is loosely mounted, by means of its integral ears 37, on the hub 29 and pinole 28, and has its outer portion 38 formed at an angle with the plane of its body portion. The forward end of the outer portion of said thread-holding arm is substantially in hook form to engage the thread when the tying mechanism is moved into contact therewith. The outer portion of the thread holding arm 36

extends forwardly between the thread-clamping fingers 34, said clamping fingers being moved during the operation of the mechanism to clamp the threads between 5 said clamping fingers and the hook of the thread-holding arm.

A spring 39 coiled about the hub 29 is attached at one end to the arm 31 and at the other end to the thread-holding arm 36, 10 and by reason of its elasticity tends to hold apart said arm 31 and the thread-holding arm 36. A stop pin 40 fixed upon the arm 17 limits the forward or spring-caused movement of the thread-holding arm 36. A 15 spring latch 41 is pivotally mounted upon the thread-holding arm 36, which latch is adapted to engage the angular upper end of the pin 35, by which engagement the thread-holding arm 36 and the bell-crank arm 31 20 are locked together. The integral arm 42 of the latch 41 also has a downwardly extending trigger pin 43, which projects through an opening 44 in the arm 36 and is adapted to engage the delay-stud 45 on the 25 arm 17. The delay-stud 45 limits the rearward movement of the arm 36 through the medium of the trigger pin 43.

The integral arm 42 of the latch 41 is adapted to be engaged by a flat spring 46 30 (Fig. 24) to hold the latch in a position to engage the angular stud 35, said spring normally holding the pin 43 against one end wall of the opening 44. The form of the spring 46 is such that it is held in position 35 without extraneous securing means. The body portion of said spring is bent over upon itself, forming the spring clamp 47, by means of which clamp the spring is firmly held upon one end of the arm 36, the ear 48 40 preventing vertical displacement of the spring.

The operation of the knot-tying mechanism is as follows: A rotation of the actuating wheel 13 communicates rotatory motion to the knotter-shaft 18 by means of the skew-gear connection between said actuating wheel and said shaft. The arm 30 having the antifriction roller 32 lying within the wave-cam-groove 15 of the actuating 45 wheel 13, is also positively moved, as is the bell-crank arm 31 and the thread-clamping arm 33 pivotally secured to said arm. The thread-holding arm 36 is moved by the cam only when its latch 41 engages the stud 35 50 on the bell-crank arm 31. When the latch 41 engages said stud the thread-holding arm is drawn back, swinging outward upon its pivotal bearing away from the tying-bill, which movement is to tighten the knot and strip the thread from the bill. As soon as 55 the latch 41 is disengaged from the stud 35, the spring 39 swings the arm 36 against the stop pin 40 (Fig. 16), said arm sliding between the clamping fingers 34. During the 60 rotation of the tying-bill the thread-clamp- 65

ing fingers 34 are moved forward upon the thread-holding arm 36, reaching the hook at its forward end and clamping the thread in said hook immediately after the necessary thread to form the loop of the knot has been 70 wound upon the rotating tying-bill. The knot-tying mechanism just described is also shown in my former Patents Nos. 672,636 and 755,110.

Each of the knotter carriages 5 is provided with a bracket having a cam-groove 50, (Fig. 13) and with a restoring shoe 51, the purpose of which groove and shoe will appear later herein. The two sides 2 and 3 are identical but oppositely arranged; one 80 of them will next be described. The side 2 comprises a longitudinally extending front bar 52 (Fig. 3) and rear bar 53. A little distance forward from the front bar 52 is an air tube 54 for receiving the ends of exhausted threads, and adjacent to this air tube is an air tube 55 for receiving the ends of the reserve threads. Forward of the air tubes 54 and 55 is a roller 56 rotatably mounted in the supporting frame, extending 85 the full length of the side, and provided in its face at intervals throughout its length with V-grooves 57. Just forward of the rear bar 53 a similar but slightly smaller roller 58 is rotatably mounted, also provided with V-grooves 59, each aligned with one of the similar grooves in the roller 56. The rollers 56 and 58 are driven by a belt (not shown) passing over the sheave 61, (Fig. 2) and by a belt 62 running over the sheaves 100 63 and 64. The peripheral speed of the rollers 56 and 58 is greater than the winding speed; said rollers do not, however, positively feed the yarn to the warp beam, but merely tend to do so, and thus serve to reduce the tension of the thread. The roller 56 reduces the tension of the yarn in the region between said roller and the guide 79. Said guide and the eye 85 increase the tension somewhat above that existing between 110 the roller 56 and the guide, but the tension is still further reduced by the roller 58. The purpose of the rollers 56 and 58 is to insure that the greatest tension shall be in the region between the bobbin and the roller 56, 115 in order that any yarn breakage shall occur in this place.

Any suitable form of bobbin-holder may be used for supporting the active and the reserve bobbins. Herein I have shown pairs 120 of bobbin-holders or pockets 66 and 67 attached to the frame member 65, one bobbin-holder of each pair being below the other. A separating shield 68 extends upwardly from each pair of bobbin pockets, each shield being in the vertical plane of one of the V-grooves 57. The bobbin pocket 66 opens on one side of the shield 68, and the pocket 67 is at the other side, so that the active and the reserve threads of each pair of bobbins 125 130

are separated by said shield. These threads are further guided from their bobbins by the fingers 69 and 70 for the pockets 67 and 66, respectively. The top and the inner sides of the roller 56 are protected by the curved shields 71, which shields are placed between the grooves 57 in said roller and hold the reserve threads from contact with the roller. Flat shield plates 72 are placed 10 over the air tubes 54 and 55, extending from the front bar 52 to the curved shields 71 and lying between adjacent reserve threads. The upper wall of the air tube 55 for the reserve threads is provided 15 with a series of openings 73, staggered in their arrangement to separate the loose ends of the threads within the tube as widely as possible and thus prevent tangling of the ends of these threads. The upper wall of 20 the air tube 54 for the ends of exhausted threads is provided with a series of slits 74 extending transversely across said tube, which openings are directly in line with the aligned V-grooves 57 and 59 in the rollers 25 56 and 58, respectively.

75 refers to the active or running thread, and 76 to its bobbin. 77 refers to the reserve thread, and 78 to its bobbin. A guide finger 79, (Figs. 2 and 11) extending forwardly from the rear bar 53, is provided 30 for each of the active threads. It will be noted that the active thread 75 running from its bobbin 76 passes over the forward roller 58, lying in the groove 57 of said 35 roller, and, passing rearwardly from said roller, extends over the air tube 55 for the ends of the reserve threads, through the slit 74 in the upper side of the air tube 54 for the ends of exhausted threads, over the 40 front bar 52, over the guide finger 79, into engagement with a detector mechanism to be hereafter described, over the rear roller 58, lying in the V-groove 59 thereof, downward from said roller and thence upward 45 in the guide channel 80, (Figs. 2 and 3) forming in said channel the loop 75, thence through the eye 81 at the upper end of said guide channel to the winding mechanism 82. A rider weight 82 on the thread of said loop 50 holds the loop distended.

The end of each reserve thread is supported upon a detector mechanism re-setted for each of said threads, which mechanism will next be described (see Figs. 11 and 12). 55 The oscillatory shaft 83 of said detector mechanism has suitable bearings in the front and the rear bars 52 and 53 and carries near its rear end a detector arm 84 having at its forward end an eye 85 through 60 which the active thread passes. A torsion spring 86, one end of which is secured to the forward bar 52 and the other end to the shaft 83, tends to oscillate said shaft and depress said detector arm into the position 65 shown in Fig. 12, which position said arm assumes when the active thread becomes exhausted. The tension of the active thread, however, normally is sufficient to hold the detector arm 84 in a horizontal position, as indicated in Fig. 11, against the torsion of 70 the spring 86. The oscillatory detector shaft 83 is also provided at its rear end with a clamping finger 87 for binding the active thread against the rear face of the rear bar 75 when the tension upon said active thread is removed, also with the two holding arms 88 and 89 for the reserve thread, the former of which is provided with a notch 88a and the latter with a notch 89a for receiving said reserve thread, which arms are 80 fixed to the shaft 83 in the same axial plane with the clamping finger 87. At its forward end the shaft 83 carries a crank arm 90 fixed thereto, which crank arm is pivotally connected at its outer end by means 89a of the connecting rod 91 with a similar crank arm 92 upon an oscillatory shaft 93 extending at a right angle with the detector shaft 83 and mounted in the bearings 94 upon the front bar 52. The pivot pins by 90 means of which the rod 91 is connected to the crank arms 90 and 92 are long enough to permit of the necessary slight "universal" movement of the ends of said rod. The shaft 93 is also provided with a downwardly extending shoe 95 and with an upwardly extending finger 96. The upper end of the finger 96 is adapted to engage the forward end of a detent pin 97 slidably mounted within a suitable opening in the 100 front bar 52, which pin is adapted to be thrust by said finger rearward into the path of one of the forks 16 fixed to the actuating gear wheel 13 of the knitter mechanism. It will thus be seen that when the tension 105 upon the active thread is materially reduced, as by the exhausting of said thread, the spring 86 oscillates the detector shaft 83, the clamping finger 87 is thrown forward, the active thread against the rear face of the rear bar 53, that pin 97 of the active thread stretched between the holding arms 88 and 89 is placed by the end of the exhausted thread, the detent pin 97 is forced forwardly into the path of one of the forks 110 115 120 125 130 135 140 145 150 155 160 165 170 175 180 185 190 195 198 200 205 210 215 220 225 230 235 240 245 250 passes, the conformation of the inclined rear end of the cam-groove 50 moves the shoe 95 to oscillate the shaft 93 and withdraw the finger 96 from the forward end of the 5 detent pin 97. The restoring shoe 51 returns the detent pin to its forward position, as indicated in Fig. 11. This oscillatory restoring movement of the shaft 93 is communicated by means of the connecting rod 10 91 to the detector shaft 83, oscillating said shaft, raising the arms 84, 88 and 89 into the position shown in Fig. 11, and withdrawing the clamping finger 87 from engagement with the formerly exhausted but 15 now active thread. The slack produced in the united threads by the casting off of said threads by the knotter, as well as the slack produced by the rising of the detector 84, is taken up by the rider 82. The normal 20 tension of the thread being restored, the detector 84 is held upward in the horizontal position shown in Fig. 11 against the downward tendency of the coiled spring 86. During the time occupied by the tying operation, and while the end of the exhausted thread was held by the clamping finger 87, the winding mechanism was supplied with 25 thread from the loop 75^a, drawing the rider-weight 82 at the bottom of said loop upward within the guide channel 80. As soon as the exhausted thread again becomes active the rider-weight gradually sinks, until it reaches a suitable stop, as, for example, the floor, thus accumulating slack in the 30 loop 75^a. Stop pins 98 (Figs. 2 and 5) limit the oscillatory movement of the detector shaft 83, the finger 99 fixed upon said shaft being adapted to engage said pins. The series of shoes 95 is normally held from 35 entering the cam-groove 50 of each passing knotter-carriage by reason of the position of the detector shafts 83. It is only when one of said shafts has been oscillated by its spring 86 that the corresponding shoe 95 is thrown into line with said cam-groove. 40

One-quarter of a rotation of the actuating gear 13 operates the tying mechanism. To stop said gear at proper intervals, a pawl 100 (Figs. 13 and 15) is provided, which 45 pawl is adapted to enter notches 101 in said actuating gear. The pawl is mounted upon a shaft 102, and is held in yielding contact with said actuating wheel by means of a coiled spring 103 extending between a crank 50 arm 104 on said shaft and a fixed point on the knotter carriage 5. After the actuation of the tying mechanism, the waste ends of the exhausted and reserve threads are drawn into the air tubes 54 and 55, respectively, 55 and removed by the air current within said tubes.

In operation, power is supplied to rotate the chain wheels 7 to travel the knotter carriages 5, to drive the means for producing 60 an air current in each of the air tubes 54

and 55, and to operate the winding mechanism 8. Full bobbins are placed within the pockets 66 and 67, the thread from one bobbin being drawn upward by the operative by the side of the separating shield 68 into the groove 57 of the forward roller 56, forward through the slit 74 in the upper part of the air tube 54, over the guide finger 79, through the eye 85 of the detector arm 84, upward into the groove 59 of the roller 58, 70 downward from said roller into the guide channel 80, through the rider-weight 82, upward through the guide channel, through the eye 81, and from thence to the winding mechanism. Thread from the other bobbin 80 is brought upward by the operative over the curved shield 71 and passed through the notches 88^a and 89^a of the arms 88 and 89 on the detector shaft 83, the end of said thread being dropped into the opening 73 in the air tube 55. When an active thread becomes exhausted, the end of the exhausted thread is drawn into the air tube 54, and the spring 86 overcoming the reduced tension upon said thread, turns the detector shaft 83, and 85 clamps the thread against the rear face of the rear bar 53. When the shaft 83 is thus turned, the arms 88 and 89 strike the exhausted thread and depress it into the path of the tying bill and thread-holding arm of the traveling knot-tying mechanisms, the reserve thread lying beside the exhausted thread. The oscillatory movement of the detector shaft 83 was also communicated to the shaft 93 through the connecting rod 91, 90 and the detent pin 97 was projected by the forward movement of the finger 96 into the path of the forks 16 of the actuating gear wheels 13. As the next preceding tying mechanism of the series approaches the exhausted thread, the cam 50 engages the shoe 95, thus accurately positioning the two threads, the tying mechanism engages said exhausted thread and that portion of the reserve thread held between the arms 88 and 100 89, and at the same instant one of the forks 16 fixed to the actuating gear 13 engages the detent pin 97. The forward movement of the knotter carriage rotates said actuating gear, and operates the tying mechanism to tie the 105 knot and shear the waste ends of the threads. As the tying mechanism travels, the threads are moved laterally far enough to clear them from the arms 88 and 89. The detent pin 97 is held in its forward position during the 110 passage of the knotter carriage by shoe 95 lying within the cam-groove 50 in said carriage, and as the knotter carriage passes the shaft 93 is restored and the detector shaft 83 oscillated to their normal positions by the 115 rear inclined portion of said cam-groove. The restoring shoe 51 upon the rear end of the knotter carriage returns the detent pin 97 to its normal position. As soon as the 120 thread is released by the clamp member 87, 130

the rider 82 sinks rapidly until the slack in the new thread has been taken up and the thread has passed under the shield 72 and into the groove 57 in the roll 56, the rider 5 thereafter sinking less rapidly until the loop 75^a is restored to normal length. The empty bobbin is removed by the operator from its pocket, and a full bobbin substituted, the end of the thread from said full bobbin being 10 placed upon the detector mechanism in the manner hereinbefore described.

It is apparent that many changes might be resorted to in the embodiment of this invention without departing from the spirit and 15 scope thereof, wherefore I desire to have it understood that I do not limit myself to the precise construction herein shown and described.

I claim as my invention:

20 1. A winder having, in combination, a mechanism for continuously winding a thread upon a beam; means for joining another thread to the thread being wound; and means for maintaining a loop in the 25 thread being wound, to furnish thread to the winding mechanism when said thread is exhausted.

2. A winder having, in combination, a mechanism for continuously winding a 30 thread; means for detecting the exhaustion of the thread being wound; means for holding a reserve thread; a normally-idle knotter to unite said threads, said knotter being controlled by the detecting means; and means 35 for maintaining a loop in the thread being wound, to furnish thread to the winding mechanism when said thread is exhausted.

3. A winder having, in combination, a mechanism for continuously winding a 40 thread; means for detecting the exhaustion of the thread being wound; means for holding a reserve thread; a stationary air tube for receiving the end of the exhausted thread; a knot-tying mechanism to unite 45 said thread; and means for maintaining a loop in the thread being wound, to furnish thread to the winding mechanism when said thread is exhausted.

4. A winder having, in combination, a 50 mechanism for winding a thread; means for detecting the exhaustion of the thread being wound; means for holding a reserve thread; a knot-tying mechanism; means actuated by the exhausting of the thread being wound 55 for actuating said tying mechanism to unite said threads; and means for maintaining a loop in the thread being wound, to furnish thread to the winding mechanism when said thread is exhausted.

60 5. A winder having, in combination, a mechanism for winding a thread; a detector mechanism; means moving with said detector mechanism for holding a reserve thread and for placing said reserve thread beside

the exhausted thread; and a knot-tying 65 mechanism to unite said threads.

6. A winder having, in combination, a mechanism for winding a thread; a detector mechanism actuated by a reduction of tension of the thread being wound; means moving with said detector mechanism for clamping 70 said thread; means also moving with said detector mechanism for holding a reserve thread and for placing said reserve thread beside the exhausted thread; a knot-tying 75 mechanism; and means actuated by the exhausting of the thread for actuating said tying mechanism to unite said threads.

7. A winder having, in combination, a mechanism for winding a thread; means for detecting the exhaustion of the thread being wound; means for clamping the exhausted 80 thread; means for holding a reserve thread; a knot-tying mechanism; means actuated by the exhausting of the thread being wound 85 for actuating the knot-tying mechanism to unite said threads; and means for maintaining a loop in the thread being wound between said clamping means and the winding mechanism, to furnish thread to the winding 90 mechanism when said exhausted thread is held by said clamping means.

8. A winder having, in combination, a mechanism for winding a thread; means for detecting the exhaustion of the thread being 95 wound; means for clamping said thread; means for holding a reserve thread; an air tube for receiving the end of said exhausted thread; a knot-tying mechanism; means actuated by the exhausting of the thread 100 being wound for actuating the tying mechanism to unite said threads; and means for maintaining a loop in the thread being wound between the clamping means and the winding mechanism, to furnish thread to 105 the winding mechanism when said exhausted thread is held by said clamping means.

9. A winder having, in combination, a mechanism for winding a thread; means for detecting the exhaustion of the thread being 110 wound; means for clamping said thread; an air tube for receiving the end of said thread when exhausted; means for holding a reserve thread and placing a portion of the reserve thread beside the exhausted 115 thread; a knot-tying mechanism; means actuated by the exhausting of the thread being wound for actuating the knot-tying mechanism to unite said threads; and means for maintaining a loop in the thread being 120 wound between said clamping means and the winding mechanism, to furnish thread to the winding mechanism when said exhausted thread is held by said clamping means.

10. A winder having, in combination, a mechanism for winding a thread; means for detecting the exhaustion of the thread being

wound; means for clamping said thread when exhausted; an air tube for receiving the end of the exhausted thread; means for holding a reserve thread and placing it beside said exhausted thread; an air tube for holding the end of said reserve thread; a knot-tying mechanism; means actuated by the exhausting of the thread being wound for actuating the tying mechanism to unite said threads; and means for maintaining a loop in the thread being wound between the clamping means and the winding mechanism, to furnish thread to the winding mechanism when said exhausted thread is held by said clamping means.

11. A winder having, in combination, a mechanism for winding a thread; a detector mechanism adapted to be actuated by a reduction of tension of the thread being wound; means moving with said detector mechanism for clamping said thread; means also moving with said detector mechanism for holding a reserve thread and for placing said reserve thread beside said exhausted thread; a knot-tying mechanism; means actuated by the exhausting of the thread being wound for actuating said tying mechanism to unite said threads; and means for maintaining a loop in the thread being wound between the clamping means and the winding mechanism, to furnish thread to the winding mechanism when said exhausted thread is held by said clamping means.

12. A winder having, in combination, a mechanism for winding a thread; a detector mechanism adapted to be actuated by a reduction of tension of the thread being wound; means adapted to move with said detector mechanism for clamping said thread; means also moving with said detector mechanism for holding a reserve thread and for placing said reserve thread beside the exhausted thread; an air tube for receiving the end of the exhausted thread; a knot-tying mechanism; means adapted to be actuated by the exhausting of the thread for actuating said tying mechanism to unite said threads; and means for maintaining a loop in the thread being wound between said clamping mechanism and the winding mechanism, to furnish thread to the winding mechanism when said exhausted thread is held by said clamping mechanism.

13. A winder having, in combination, means for winding a thread, means for detecting the exhaustion of the thread, means having movement with the detecting means for holding a reserve thread and for placing the reserve thread beside the exhausted thread, and means for uniting said threads.

14. A winder having, in combination, a mechanism for winding a thread; means for holding a bobbin; and two positively-driven rollers for supporting the thread between said bobbin and said winding mechanism,

the surface of the roller nearer the bobbin-holding means moving at a higher speed with reference to said thread than that of the other roller.

15. A winder having, in combination, a mechanism for winding a thread; means for holding a bobbin; two positively-driven rollers for supporting the thread between said bobbin and said winding mechanism, the surface of the roller nearer the bobbin-holding means moving at a higher speed with reference to said thread than that of the other roller; and a weight adapted to place tension upon said thread between said rollers.

16. A winder having, in combination, a mechanism for winding a thread; a positively-driven roller for supporting said thread; a mechanism for detecting the exhaustion of the thread being wound; means for holding a reserve thread; a knot-tying mechanism; means actuated by the exhausting of the thread being wound for actuating said tying mechanism to unite said threads; and means for maintaining a loop in the thread being wound, to furnish thread to the winding mechanism when said thread is exhausted.

17. A winder having, in combination, a mechanism for winding a thread; two positively-driven rollers for supporting the thread being wound; means for detecting the exhaustion of said thread; means for holding a reserve thread; a knot-tying mechanism; and means for actuating the tying mechanism to unite said threads at a point between said rollers.

18. A winder having, in combination, a mechanism for winding a thread upon a beam; a thread-uniting mechanism; means for holding stationary a portion of the thread being wound during the operation of said thread-uniting mechanism; and means for maintaining a loop in the thread between the winding mechanism and said thread-holding means.

19. A winder having, in combination, a mechanism for winding a thread; a thread-uniting mechanism; means for presenting a reserve thread to said thread-uniting means; means moving with said presenting means for clamping the thread being wound at a point between said winding mechanism and said thread-uniting mechanism; and means for maintaining a loop in the thread being wound between said clamping means and said winding mechanism.

20. A winder having, in combination, a mechanism for winding a warp; devices for holding a reserve thread in proximity to each warp thread; a thread-uniting means; and means for recurrently moving said thread-uniting means into proximity to said threads.

21. A winder having, in combination, a

mechanism for winding a thread; means for detecting the exhaustion of the thread being wound; means for holding a reserve thread in proximity to the thread being wound; a normally idle thread-uniting means; means for recurrently moving said thread-uniting means into proximity to said threads; and means actuated by the exhausting of the thread being wound for actuating the thread-uniting means to unite said threads.

22. A winder having, in combination, a bobbin holder, means for unwinding thread from a bobbin in said holder, two positively-driven rollers for supporting the thread between the bobbin and the unwinding means, the roller nearer the bobbin having a greater surface speed than the winding speed of the thread, and knot-tying means arranged to operate upon said thread at a point between said rollers.

23. A winder having, in combination, a bobbin holder, means for unwinding a thread from a bobbin in said holder, two positively-driven tension-reducing rollers for supporting the thread between the bobbin and the unwinding means, a reserve-bobbin holder, means for supporting the end of the thread on the reserve bobbin adjacent to the other thread, and means arranged to operate at a point between said rollers for uniting said threads.

24. In a textile machine, in combination, an endless track; a knot-tying mechanism; an endless chain having an engagement with said knot-tying mechanism; and means for moving said chain to travel said knot-tying mechanism around said track.

25. In a textile machine, in combination, two wheels; an endless belt running over said wheels; and a knot-tying mechanism connected with said belt.

26. A winder having, in combination, an oscillatory shaft, means tending to rock said shaft, means on said shaft to engage an active thread, the tension of the active thread being sufficient to prevent movement of said shaft, means connected with said shaft for supporting a reserve thread, and a knot-tying mechanism adapted to tie said threads together.

27. A winder having, in combination, a bobbin holder, a mechanism for unwinding a thread from a bobbin in said holder, a knot-tying mechanism adapted to operate upon the thread at a point between the bobbin holder and the unwinding means, means for clamping the thread at a point between the first mentioned point and the unwinding means, and means for maintaining a loop in the thread intermediate the clamping means and the unwinding means.

28. A winder having, in combination, a series of bobbin holders, means for unwinding thread from bobbins in said holders, a

suction conduit extending transversely of the threads being wound, said conduit having an opening therein adjacent to each thread, means for supporting a reserve thread adjacent to each of the other threads, a suction conduit having openings to receive the ends of the reserve threads, and means for uniting reserve threads to the other threads upon exhaustion of the latter.

29. The combination of a traveling knotter, a non-traveling knotter-actuating member, means for placing said member in operative relation to the path of the knotter, and means for withdrawing said member from such position.

30. The combination of a knotter, a knotter-actuating member, thread-controlled means for placing said member in operative relation to the knotter, means for resetting said placing means, and means for withdrawing said member from operative position.

31. The combination of a knotter arranged to travel, a member movable into the path of the knotter for actuating the latter, means for so moving said member, and means traveling with the knotter for withdrawing said member.

32. A winder having, in combination, a mechanism for winding a thread; means for holding a reserve thread; a normally idle knot-tying mechanism; means for moving said knot-tying mechanism in a circuit, a portion of which circuit is in proximity to a portion of the thread being wound and a portion of the reserve thread; and means actuated by the exhausting of the thread being wound for actuating the knot-tying mechanism to unite said threads.

33. A winder having, in combination, a mechanism for winding a thread; means for detecting the exhaustion of the thread being wound; means for clamping the exhausted thread; means for holding a reserve thread; a normally idle knot-tying mechanism; means for moving said knot-tying mechanism in a circuit, a portion of which circuit is in proximity to a portion of the thread being wound; and means actuated by the exhausting of the thread being wound for actuating the knot-tying mechanism to unite said threads.

34. A winder having, in combination, a mechanism for continuously winding a thread; a knot-tying mechanism; means for moving said knot-tying mechanism in a circuit, a portion of which circuit extends transversely of and beneath a portion of the thread being wound; and means for maintaining a loop in the thread being wound, to furnish thread to the winding mechanism when said thread is exhausted.

35. A winder having, in combination, a mechanism for continuously winding a thread; means for holding a reserve thread;

- a knot-tying mechanism; means for moving said knot-tying mechanism in a circuit, a portion of which circuit is in proximity to a portion of the thread being wound; and
- 5 means for maintaining a loop in the thread being wound, to furnish thread to the winding mechanism when said thread is exhausted.
36. A winder having, in combination,
- 10 means for supporting an active thread; a mechanism for detecting the exhaustion of said thread; means moving with said detector mechanism for placing a reserve thread beside the exhausted thread; and a
- 15 knot-tying mechanism adapted to tie said threads together.
37. A winder having, in combination,
- 20 means for supporting a thread; a detector mechanism having an engagement with said thread; means moving with said detector mechanism for supporting a second thread and for placing said second thread beside the first mentioned thread; and a
- 25 knot-tying mechanism adapted to tie said threads together.
38. A winder having, in combination, an oscillatory shaft; means tending to rock said shaft; means on said shaft adapted to engage an active thread, the tension of said active thread being sufficient to prevent a movement of said shaft; and means connected with said shaft for supporting a reserve thread.
39. A winder having, in combination, an oscillatory shaft; means tending to rock said shaft; means on said shaft adapted to engage an active thread, the tension of said active thread being sufficient to prevent a movement of said shaft; and means on said shaft adapted to clamp said thread when exhausted.
40. A winder having, in combination,
- 45 means for winding threads upon a beam, a tying mechanism, means for clamping exhausted threads for the tying operation, and means for maintaining loops in the threads, said loops furnishing yarn to the winding means while exhausted threads are clamped.
41. A winder having, in combination,
- 50 means for winding a thread upon a beam, thread-clamping means adapted to stop the travel of said thread at one point; and means for maintaining a loop in said thread intermediate said first-mentioned two means.
42. A winder having, in combination, a mechanism for winding a thread upon a beam, non traveling means for intermittently clamping said thread; and means for maintaining a loop in said thread between said winding mechanism and said clamping means.
43. The combination of a carriage, a knotter on the carriage, a member movable into the path of movement of the knotter for actuating the latter, thread-controlled means
- for so moving said member, a cam on the carriage for restoring said thread-controlled means, and a cam on said carriage for withdrawing said member.
44. In a textile machine, in combination,
- 70 movable means for supporting a reserve thread, a traveling knot-tying mechanism, and means moving with said knot-tying mechanism for moving said supporting means into normal position.
45. In a textile machine, in combination,
- 75 a rock shaft carrying a detector device and a reserve-thread support, a movable member operatively connected with said shaft, a traveling knot-tying device, and means connected with said knot-tying device and adapted to engage and move said member.
46. A winder having, in combination,
- 80 a knot-tying mechanism; means for moving said mechanism in an endless path; detector mechanism, knotter-actuating mechanism, thread-guiding means and bobbin-supports arranged along said path; and a winding mechanism.
47. A winder having, in combination,
- 85 means for winding a series of threads; a series of knotter actuators, one for each thread; a carriage arranged to travel continuously along the series of actuators; and a normally idle knotter mounted on the
- 90 carriage and arranged to be actuated by said actuators during the continuing travel of the carriage.
48. A winder having, in combination,
- 95 means for supporting a plurality of active thread supplies; means for winding a plurality of threads; means for supporting a reserve thread supply; a detector for each active thread which functions when its thread supply is exhausted; and a plurality
- 100 of traveling knotters which travel in the vicinity of the active threads, the first knotter which arrives in the neighborhood of an exhausted thread being controlled by the detector for that thread to tie said thread to a
- 105 reserve thread.
49. A winder having, in combination,
- 110 means for supporting a plurality of active thread supplies; means for winding a plurality of threads; means for supporting a
- 115 reserve thread supply; a detector for each active thread which functions when its thread supply is exhausted; a knotter actuator controlled by each detector; and a plurality
- 120 of traveling normally-idle knotters, the first knotter which arrives in the neighborhood of an exhausted thread being actuated by the actuator corresponding to said thread to tie said thread to a reserve thread.
50. A winder having, in combination,
- 125 means for winding a thread, a knotter arranged to travel continuously, a detector to detect exhaustion of the thread, and non-traveling detector-controlled means for
- 130

laterally moving the thread, when exhausted, into the path of the knotter.

51. A winder having, in combination, means for winding a thread, a detector to detect exhaustion of the thread, a detector-controlled clamp to clamp the thread when exhausted, a knotter arranged to travel transversely of the thread, and detector-controlled means for laterally moving the thread, when exhausted, into the path of the knotter.

52. A winder having, in combination, bobbin-supporting means, section-beam-rotating means, the beam being arranged to

draw the threads from the bobbins by its own pull, guides around which the threads extend in passing from the bobbins to the beam, and means to reduce the tension created by the passage of the threads around the guides, said tension-reducing means comprising a roller over which the threads run, said roller being driven at a greater surface speed than the speed of the yarn.

HOWARD D. COLMAN.
